UNITED STATES PATENT OFFICE.

GEORGE MARKLE, OF BRANTFORD, CANADA, ASSIGNOR TO THE RUDDY MANUFACTURING COMPANY, LIMITED, OF BRANTFORD, CANADA.

WIRE QUEEN EXCLUDER FOR BEEHIVES.

Application filed March 17, 1927. Serial No. 176,145.

My invention relates to improvements in wire queen-excluders for bee hives and the object of the invention is to devise a queen excluder which will provide a properly dimensioned bee space, thus eliminating the resultant disadvantages of an improperly dimensioned bee space, such as the building of burr comb in the bee space; a further object is to provide a wire excluder of 10 extremely open construction, so that the ventilation of the hive will be interfered with to a minimum degree; a still further object is to provide a construction of great strength without interfering with the bee 15 space.

My invention consists in the construction and arrangement of parts, all as hereinafter more particularly described and illustrated in the accompanying drawings in which: 20 Fig. 1 is a plan view of a queen excluder constructed in accordance with my invention.

Fig. 2 is a vertical section through a bee 25 hive showing my excluder therein, the section being taken on a line corresponding to the line 2—2 of Fig. 1.

Fig. 3 is a fragmentary view, to a larger scale, showing the manner in which certain wires used in my device are imbedded within 30 a supporting frame.

Fig. 4 is a fragmentary view, also to a larger scale, showing the manner in which ribs are cast about the wires, one of which wires is shown in Fig. 3, and also showing the manner in which these ribs are embedded 35 in the frame of the device.

Fig. 5 is a fragmentary view, to an enlarged scale of a portion of Fig. 2, showing the relative position of my excluder to the 40 brood chamber and super of a bee hive.

In the drawings like characters of reference indicate corresponding parts in the various views.

My improved queen excluder consists of 45 a rectangular wooden frame 1, in which is supported a screen-like structure formed from a plurality of equally spaced apart wires 2 disposed parallel to two opposite marginal edges of the frame 1.

Adjacent to each end, each wire 2 is bent 50 at 3 to offset the ends 4 of the wire out of the plane of the central portion of the wire.

The offset ends 4 are imbedded within the 55 frame 1 and the bent portions 3 are such that the central portions of the wires 2 are

displaced towards one face of the frame 1 and away from the other face.

A plurality of spaced apart metal ribs 5 are cast about the wires 2 and these ribs extend in one piece entirely across the frame 60 and the ends of the ribs are imbedded in the frame as shown in Fig. 4.

These ribs 5 serve to accurately retain the wires 2 in their properly and equally spaced apart positions and the faces A of 65 the ribs are flush with the corresponding face of the frame 1.

Also the wires 2 are as near as can be had to the faces A of the ribs 5, so that these faces of the wires are substantially 70 flush with that face of the frame.

It will thus be seen that, in my device, one face of the excluding screen is substantially flush with one face of the frame, whereas the other face of the screen is depressed below the opposite face of the frame and the extent to which it is depressed is 75 exactly the height of the bee space desired.

In using my excluder in a hive, it is placed between the brood chamber 6 and 80 the super or surplus honey box 7.

Reference is now directed to Figs. 2 and 5 from which the use of my device will be clear.

In the standard hive, the bottom of the 85 comb 8 in the super 7 is flush with the bottom of the super and the top of the comb 9 in the brood chamber 6 is depressed below the top of the brood chamber a distance 90 equal to the height of the bee space desired. This bee space in the brood chamber 95 is indicated by the numeral 10.

In my excluder, due to the manner in which the wires 2 are bent at 3, so as to displace the wire screen towards one side of the 95 frame 1 and away from the other side, the under face of the screen is substantially flush with the under face of the frame 1 and when the super is placed upon the excluder, a bee space 11 of exactly the proper height is provided above the screen.

The construction of my excluder is such that an extremely open structure is provided so that the efficient ventilation of the hive is interfered with to a minimum degree.

This is accomplished by the provision of the ribs 5 which extend entirely across the frame in one single piece.

A further important feature of my invention is that the bee spaces above and be- 110

low the excluder may be very exactly and accurately dimensioned which feature is of great value.

From the foregoing it will be evident that

5 I have devised valuable improvements in queen excluders whereby the objects of my invention have been attained.

Various modifications may be made in my invention without departing from the spirit 10 thereof or the scope of the claims and therefore the exact forms shown are to be taken as illustrative only and not in a limiting sense and I desire that only such limitations shall be placed thereon as are imposed by 15 the prior art or are specifically set forth in the appended claims.

What I claim as my invention is:

1. A queen excluder for bee hives comprising, a rectangular frame, a plurality of 20 spaced apart wires extending thereacross and disposed parallel to two opposite marginal edges of the frame, the ends of each wire offset and imbedded in the frame, the

wires lying in a common plane and forming a screen-like structure one face of which is 25 substantially flush with one face of the frame and the other face of which is depressed below the plane of the opposite face of the frame.

2. A queen excluder for bee hives comprising, a rectangular frame, a plurality of spaced apart wires extending thereacross and disposed parallel to two opposite marginal edges of the frame, the ends of the wires imbedded within the frame, the wires offset at 30 each end thereof so that the central portions of the wires are displaced laterally towards one face of the frame and away from the opposite face, and a plurality of spaced apart, cast metal ribs extending across the 35 frame at right angles to the aforesaid wires, the wires imbedded within said ribs, and the ends of the ribs imbedded in the frame, each rib extending in one piece across the 40 frame.

GEORGE MARKLE.
